[57] CLAIM

The ornamental design for a combined electrical rocker switch and panel, as shown and described.

DESCRIPTION

FIG. 1 is a side elevational view of a combined electrical electric switch rocker and panel embodying this invention;

FIG. 2 is a top plan view of FIG. 1;

FIG. 3 is both a left side and a right side, elevational view of FIG. 1;

FIG. 4 is a front end elevational view of FIG. 1, and,

FIG. 5 is a rear end elevational view of FIG. 1.
The broken lines showing throughout the drawing figures is included for the purpose of illustrating environmental structure only and formed no part of the claimed design.

FIG. 1

FIG. 5

FIG. 2

FIG. 4

FIG. 3
